UNITED STATES PATENT OFFICE.

ROBERT P. ALLISON, OF BALTIMORE, MARYLAND, ASSIGNOR, BY MESNE ASSIGNMENTS, TO MOTOR WHEEL CORPORATION, OF LANSING, MICHIGAN, A CORPORATION OF MICHIGAN.

DISK WHEEL.

Application filed February 3, 1919. Serial No. 274,719.

The primary object of the invention is the provision, in a disk wheel, of ready access from the front of the disk to the valve stem which ordinarily emerges from the felly at the rear of the disk.

Many expedients have been proposed to effect access from the front of the wheel by the employment of special valve stems and attachments; but by my invention I am able to employ the usual straight valve stem having its axis approximately in the median plane of the wheel at the rear of the disk adjacent the wheel periphery and, without materially weakening or marring the symmetrical curvature of the disk, enable the valve stem end to be coupled at the front of the disk with the nipple of an inflation hose.

I accomplish this result by carrying the general curvature of the disk from in front of the valve stem near the wheel periphery to the rear of the same in the medial wheel portion, the disk crossing the valve stem axis, whether or not precisely in the median plane of the wheel; and providing an aperture at or adjacent the point of intersection for enabling an air coupling to be effected.

Advantageously the intersection of the disk and valve stem axis is at some point intermediate the valve stem length, the disk being there apertured to provide a passageway permitting the stem to extend through the disk to the front of the wheel, thus avoiding any material weakening or disfiguring of the disk as would result from the provision of a hand hole.

A preferred embodiment of the invention is set forth for illustrative purposes only in the accompanying drawing and in the following description based thereon.

In the drawing—

Fig. 1 is a front elevation of a wheel embodying the invention; and

Fig. 2 represents such a wheel in diametric section.

Referring to the drawings by reference numerals, the wheel includes a hub portion 1 and a felly or rim portion 2 carrying a pneumatic tire 3. The main disk portion 4 is shown as riveted or otherwise fixedly secured to the hub at 5 and to the rim at 7, while a secondary disk 6 is also shown as riveted or otherwise fixedly secured to the

hub at 8 and to the main disk at 9. Adjacent the rim the disk is curved from the front rearwardly across the median wheel plane as indicated at 10, forming a forwardly facing recess or concave zone. Into this recess the valve stem or casing 11 and the valve cap 12 extend through an opening formed in the disk, thereby rendering the cap and valve stem readily accessible from the front of the wheel for testing and inflation purposes.

What I claim and desire to secure by Letters Patent is:

1. A wheel disk having peripheral corrugations including a zone intersecting the central plane of the tread and the position of the valve stem and dust-cap at an angle of approximately 90°, the said portion being apertured to admit said members, the corrugations including a concavity adjacent said aperture curved away from the central plane of rotation of the wheel providing convenient access to the valve.

2. A disk wheel comprising an inner hub portion, an outer tire-carrying portion, a medial body portion, and a pneumatic tire peripherally mounted thereon and having a substantially straight valve stem the axis of which normally coincides substantially with the median plane of the tire, the disk body having a part extending inwardly from in front of the valve stem towards the rear and apertured adjacent the inner end of the valve stem to afford access thereto from the front for inflating.

3. A disk wheel comprising an inner hub portion, an outer tire-carrying portion, a medial body portion, and a pneumatic tire peripherally mounted thereon and having a substantially straight valve stem the axis of which normally coincides substantially with the median plane of the tire, the disk body having a part extending inwardly from in front of the valve stem towards the rear across the median plane of the tire and apertured adjacent the point of interception of the valve stem axis to afford access to the valve stem from the front for inflating.

4. A disk wheel comprising an inner hub portion, an outer tire-carrying portion, a medial body portion, and a pneumatic tire peripherally mounted thereon and having a substantially straight valve stem the axis of which normally coincides substantially with

- the median plane of the tire, the disk body having a part extending inwardly from in front of the valve stem towards the rear inwardly from in front of the valve stem
- 5 towards the rear across the median plane of the tire and apertured at the point of interception of the valve stem axis, the valve stem extending through the aperture to afford access to the valve stem from the
- 10 front for inflating.
5. A disk wheel comprising an inner hub portion, an outer tire-carrying portion, a medial body portion, and a pneumatic tire peripherally mounted thereon and having an
- 15 inwardly extending valve stem the axis of

which normally coincides with the median plane of the tire, the disk body having an annular forwardly facing depression, the outer wall of the depression extending from in front of the valve stem towards the

20 rear across the median plane of the tire and provided with an aperture in line with the valve stem axis through which the valve stem projects to the front of the disk to afford convenient access thereto for inflating.

Signed by me at Baltimore, Maryland,
this 31st day of January, 1919.

ROBERT P. ALLISON.
